ROTARY VANE-TYPE INTERNAL
COMBUSTION MOTORRodolfo Stephens-Castaneda, Av. del Taller 92-8,
Mexico City, MexicoFiled Apr. 24, 1961, Ser. No. 105,010
3 Claims. (Cl. 123—16)

This invention relates to a rotary vane-type internal combustion motor.

It is the principal object of the present invention to provide a rotary vane-type internal combustion motor, in which the vanes plungers are movable in and out of the rotor and in which the supply of fuel is extended to the rear of the pistons to be compressed by the plungers and forced into the spaces on the periphery of the rotor for delivery to the combustion chamber under pressure.

It is another object of the invention to provide a rotary vane-type internal combustion motor with sockets for containing the vane plungers so that they can readily adapt themselves to the interior face of the main housing to ensure against leakage between the spaces of the main piston.

It is still another object of the invention to provide a rotary vane-type internal combustion motor in which the radial movement of the vanes is positively effected.

It is a further object of the invention to provide a rotary vane-type internal combustion motor which will have adequate lubrication for maintaining the motor of the type substantially cool.

Other objects of the invention are to provide a rotary vane-type internal combustion motor, having the above objects in mind, which is of simple construction, inexpensive to manufacture, easy to assemble and keep in repair, has a minimum number of parts, compact, light in weight, efficient and effective in use.

For a better understanding of the invention reference may be had to the following detailed description taken in connection with the accompanying drawing, in which

FIGURE 1 is an elevational view of the rotary vane-type internal combustion motor embodying the features of the present invention with one half portion being broken away and shown in section.

FIG. 2 is a vertical sectional view of the internal combustion motor as viewed generally on line 2—2 of FIG. 1.

FIG. 3 is a vertical elevational view of the internal combustion motor, one of the end plates having been removed to look in plan upon the interior of the main housing and upon the rotor, one half section looking upon the end of the rotor bearing assembly carried by the end plate, and

FIG. 4 is an end elevational view similar to FIG. 3 of the internal combustion motor with the end plate and the piston carrying rotor removed and looking in plan upon the inner face of the opposite end plate.

Referring now to the figures, 10 represents a main housing ring part having air cooling fins 11 on its outer periphery and an internal circular wear surface 12 on its inner periphery and providing a circular work chamber 13. Within the work chamber 13, there is a piston-carrying rotor 14 that rotates about an axis indicated at 15 upwardly offset from the axis of the chamber 13 indicated at 16 in an eccentric manner. On the opposite sides of the main housing ring 10 are motor and plates 17 and 18 that are secured to the main housing ring 10 respectively by fastening bolts 19 and 21. These end plates 17 and 18 respectively have foot portions 22 and 23 on which the motor is supported and held upright. On the top of the main housing, there is extended a hoisted ring 24 by which the motor can be lifted and transported.

2

The rotor 14 has a circular outer peripheral surface 26 against which a seal member 27 is pressed by a compression spring 28, both of which lie in a recess in the top of the main housing ring 10. This is to seal off at the top of the motor the combustion side of the chamber 13 from the intake side of the chamber.

On the intake or combustion side of the chamber 13 and in the inner periphery 12 of the main housing 10 is an arcuate recess 29 extending clockwise as viewed in FIG. 1 from a transverse slot 31 in the periphery 12 for nearly a quarter turn to a point 32. In the respective end plates 17 and 18 are respectively side slots 33 and 34 also extending from the transverse slot 31 and that run co-extensively with the recess 29 and taken therewith provide the explosion chamber in which the carbureted mixture is released under pressure. A spark plug 36 is fixed within an opening 37 in the end plate 18 at the end of the transverse slot 31 in the main housing 10. The spark plug 10 is connected to an ignition coil not shown to ignite the gases delivered in the explosion chamber.

Disposed respectively in the respective end plates 17 and 18 are respective ball bearing assemblies 38 and 39 that support a rotor axle 41 having shoulders 42 and 43 against which the respective ball bearing assemblies fixed to hold the shaft against axial displacement from the rotor. Ball bearing retaining plates 44 and 46 are secured respectively by fastening screws 47 and 48 to the respective end plates 17 and 18 to hold the ball bearing assemblies in place.

Ring guides 51 and 52 are respectively disposed in respective circular recesses 53 and 54 and upon respective roller bearing assemblies 56 and 57 on reduced diameter portions 59 and 61 and held in place thereover and within the recesses by respective inner retaining plates 62 and 63 fastened to the end plates by any suitable means. Between the respective ring guides 51 and 52 and the outer periphery of the respective recesses 53 and 54, there are provided pairs of pins 64 which carry vanes 66 and by these pins that project into the respective recesses from the respective sides of the rotor and the recess being eccentric to the rotor axis will cause the vanes 66 to move positively radially inwardly and outwardly in respective recesses 68 in adjustable sockets 69 and lying within sleeve 71 that are angularly adjustable in cylindrical socket recesses to permit the outer end face of the vanes to adapt themselves to the periphery of the main housing ring 10 to provide a main ring housing chamber. The rotor 14 is keyed to the shaft 41 by a key 73, FIG. 1.

The side faces of the rotor are provided with concentric annular recesses 74 and 75 on one face and 77 and 78 on the other face. These recesses 74 and 75 carry respectively rotor oil rings 79 and 80 and 81 and 82. These rings bear against the internal bearing retaining plates 62 and 63 and the respective end plates 17 and 18 to provide sealing engagement therewith and keep the oil against leakage toward the axle 41 and the combustion chamber 13. The motor is supplied oil through holes 83 and 84 in the respective end plates 17 and 18.

On the inner faces of the inner plate 63 is an arcuate recess 85 that receives gas mixture from supply passage 86 in end plate 18 and pipe 87 that leads from a carburetor. The gas mixture is taken into vane spaces 88 and is forced out of the vane spaces through arcuate slot 89 on plate 62 and passage 91 to chamber 13 and thereby compressed and delivered to peripheral spaced pockets 92 in the rotor outer surface 26.

The rotor 14 rotates clockwise and the vanes are worked in and out by the pins traversing the eccentric annular recesses 53 and 54. After the combustion the product passes through exhaust port 93 at the bottom of the housing ring 10 to the atmosphere. The fuel en-

ters the vane recesses 88 from one side of the rotor and is forced by the vanes to the other side of the rotor for discharge into the spaces between vanes through the passage and whereupon it is compressed into the pockets 92 of the outer periphery and finally released into the combustion space and exploded to effect the rotation of the rotor. These explosions take place in sequence causing steady rotation of the rotor. A safety valve 94 is provided in a hole 95 in the housing 10 to release excess pressure.

The length of the explosion chamber is important as an explosion chamber should be kept well away from the entrance of the fresh gas mixture into the vane spaces and should there be a premature explosion, the safety valve 94 in the upper part of the motor will open. Suction, compression, explosion and exhaust are accordingly effected in sequence to effect the steady rotation of the rotor.

While various changes may be made in the detailed construction, it shall be understood that such changes shall be within the spirit and scope of the present invention as defined by the appended claims.

What is claimed is:

1. A radial vane-type internal combustion motor comprising a main ring housing, end plates connected to the sides of the main housing, a vane rotor having an axial shaft journaled in said end plates and eccentrically disposed in said main housing, said rotor having longitudinally-extending cylindrical socket recesses, angularly adjustable vane sockets operable in said socket recesses, radially adjustable vanes in said angularly adjustable vane sockets of the rotor having wiping contact with the inner surface of the housing, slot means provided in the inner surface of the main housing and in the end plates at the opposite sides thereof to provide an explosion chamber within the housing surface, said cylindrical vane socket rotor having vane spaces in which the vanes are adjusted, passageway means in one end plate for supplying gas mixture to the inner end of the vane spaces whereby the gas mixture will be acted upon by the vanes, passage way means in the opposite end plate for delivering the gas

mixture by the inward movement of the vanes from the vane spaces to the opposite side of the rotor and to the housing removed from the explosion chamber, said rotor having slots in its periphery into which the gaseous mixture from the main ring housing chamber is compressed, means within the explosion chamber of the chamber for igniting the compressed gas mixture as it is delivered from the rotor slots thereto, and spaced pin and slot means extending between the vanes and the end plates for working the vanes radially in their spaces in the cylindrical vane sockets toward and from the inner periphery of the main housing.

5 2. A rotary vane-type internal combustion motor as defined in claim 1, and said spaced pin and slot means for causing the radial adjustment of the vanes including circular recesses in the respective end plates, ball bearing assemblies in said recesses, guide rings supported on said ball bearing assemblies and pairs of spaced pins extending laterally from the opposite sides of the vanes into the recesses of the end plate radially outwardly of the guide rings.

10 20 3. A rotary vane-type internal combustion motor as defined in claim 2, and inner plates secured to the end plates within said circular recesses and serving to hold the bearing assemblies therewithin and said supply and delivery passageway means being in the form of arcuate recesses lying in the inner faces of said bearing retaining plates.
